CLAIM

The ornamental design for a tongue, as shown and described.

DESCRIPTION

FIG. 1 is a top perspective view of a tongue showing our new design;

FIG. 2 is a bottom perspective view of the tongue of FIG. 1;

FIG. 3 is a top plan view of the tongue of FIG. 1;

FIG. 4 is a bottom plan view of the tongue of FIG. 1;

FIG. 5 is a rear elevational view of the tongue of FIG. 1;

FIG. 6 is a front elevational view of the tongue of FIG. 1;

FIG. 7 is a right side elevational view of the tongue of FIG. 1; and,

FIG. 8 is a left side elevational view of the tongue of FIG. 1.

The broken lines in the drawings represent portions of the tongue and form no part of the claimed design.

1 Claim, 8 Drawing Sheets
